CENTRIFUGE SYSTEMS

Richard H. Selkirk, New Brunswick, N. J., assignor to the United States of America as represented by the United States Atomic Energy Commission

Application March 25, 1948, Serial No. 16,901

3 Claims. (Cl. 233—23)

My invention relates to centrifuges, and more particularly to centrifuge systems for separating radioactive liquids, mixtures, or materials.

The use of centrifuges in the chemical industry is well known, and various types of centrifuges have been employed. Examples of these may be found in the patents to Peck, 560,631; Reese, 1,981,924; Boss, 1,071,870, and Anderson, 2,265,053.

In normal industrial chemical processes the problem of providing suitable centrifuges for the separation of precipitates is usually not a major one since, relatively simple structures may be used where the motors or other driving mechanism can be located close to the centrifuge. Also, such centrifuges may be directly inspected, cared for and repaired, since they are ordinarily accessible at all times and immediate danger of injury from the escaping mixture or spillage of the chemical materials being handled is not present in the ordinary processes.

In contrast to the foregoing, the processing of radioactive materials in a centrifuge may involve many additional problems, and the utilization of conventional, readily obtainable commercial centrifuges is, in many instances, not possible. For example, in the processing of strongly radioactive materials, centrifuges must operate within shielded cells by remote control. Trouble may arise from the escape of liquid or the climbing of the liquid up the drive shafts, or into the bearings. This presents a problem not only of corrosion, but of radiation. Also the decontamination and cleaning of such equipment is much more difficult.

Since this equipment is operated behind shielding or in a shielded chamber, usually having thick concrete walls, it may require days to halt the processes being carried out therein and clear away the shielding for access to the equipment, when repair, or reconditioning becomes necessary. Accordingly, the equipment used under such circumstances must be so constructed as to require a minimum of attention, repair, or replacement.

Applicant, with a knowledge of the difficulty of adapting the structures of the prior art to the processing of radioactive materials, has for an object of his invention the provision of a centrifuge particularly adapted for handling radioactive liquids and for separating precipitates therefrom.

Applicant has as another object of his invention the provision of a centrifuge which may be actuated and controlled at a distance therefrom.

Applicant has as another object of his invention the provision of a remotely controlled centrifuge which may be actuated and controlled through a barrier, while obstructing the passage of harmful radiations.

Applicant has as another object of his invention the provision of a remotely controlled centrifuge whose actuating equipment may be positioned outside of the radiation barrier or shield where it may be readily accessible for inspection, repair, or replacement.

Applicant has as another object of his invention the provision of a remotely actuated and controlled centri-

2

fuge whose bowl is journaled in a bearing to provide a rugged durable structure.

Applicant has as a further object of his invention the provision of a centrifuge with seals and a pressure system to prevent the radioactive liquid being treated from contaminating the lubrication or attacking the vulnerable parts of the machine.

Other objects and advantages of my invention will appear from the following specification and accompanying drawings, and the novel features thereof will be particularly pointed out in the annexed claims.

Fig. 1 is a side elevation illustrating the complete installation of one form of my improved centrifuge and associated parts in a shielded cell.

Fig. 2 is a sectional elevation of the shaft housing with the shaft disposed therein for actuating the centrifuge.

Fig. 3 is a partial sectional view showing in detail the centrifuge construction and its connection with the driving shaft.

Fig. 4 is a partial sectional view of the housing inclosing the driving motor, tachometer, and associated elements of the first form of my invention.

Fig. 5 is a detail of the coupling employed in the driving mechanism for my improved centrifuge.

Fig. 6 is a side elevation, partly in section, of a modified form of centrifuge embodying an under-support for the centrifuge basket.

Referring to the drawings in detail and particularly to Fig. 1 wherein a housing 2 is employed to inclose a driving mechanism or motor and associated elements which will be described more in detail in connection with Fig. 4,

Fig. 2 is a sectional elevation of the shaft housing with the shaft disposed therein for actuating the centrifuge. A peripheral flange 100 is formed on the lower extremity thereof for abutment with a similar flange 101 on housing or shielding plug mechanism 3 which incloses and is associated with an elongated power transmitting shaft including sections 9, 10 which may extend through several feet of shielding such as concrete 7, and into a cell or closed chamber within which the centrifuge is positioned. Appropriate bolts passing through registering openings in the flanges may be employed to secure them together.

Joined to the lower end of housing 3 and extending downwardly therefrom is a casing 4 for inclosing the driving mechanism for the centrifuge. This casing provides an anti-friction bearing and a liquid barrier for the shaft 72. Yoke 130 serves as a support for this arrangement by providing a pair of legs which straddle the casing 23 and rest on the base. It is joined to the lower flanged portion of housing 3 by studs 131.

The cell or chamber inclosing the equipment has walls 50 which provide a barrier against harmful radiations, and these walls may be of concrete several feet thick as indicated at 7 in Fig. 1. Under these conditions, it is a difficult problem to pass a drive shaft through this shielding to the internally positioned centrifuge, and to house 55 the shaft in an offset manner to obviate the leakage and harmful effects of escaping radiations through the plugged opening in the shielding. Provision must also be made for hoisting the drive shaft assembly out of the shielding in the event that a new drive shaft is to be inserted.

A similar problem is also involved in connection with the arrangement employed to remotely control the operation of the skimmer for the centrifuge bowl, described herein-after.

As shown in Fig. 2, the housing 3 may be made up of 65 a plurality of cylindrical members exemplified by members 8 and 8' which members become progressively smaller in diameter as the inner wall of the seal is approached. By such a construction, radiations are prevented from escaping to the outside from the cell, between the junction of the housing with the shielding 7.

Likewise the drive shaft within the housing 3 is constructed along somewhat the same principles, in that shaft

portion 9 may be somewhat larger than shaft portion 10 and so on. In this way the shaft becomes progressively larger from the inside to the outside of the cell. To further reduce the possibility of escape of radiations axially of the shaft, and to provide supports with a minimum of friction, separate bearings, such as 13, are disposed about the shaft at the junctures of its various sections or at convenient intervals. In the bearings 13, spaced inner and outer elements 104, 105 provide a race for the ball bearing element 106. The inner element 104 is held in place by nut 107 and appropriate washers. Interposed between the shaft sections 9 and 10 and the cylindrical sections 60, 61 are inverted cup-shaped elements 14, 14 of shielding material which are adapted to receive the bearings 13 and serve to guide shaft sections 9, 10 in their rotation. They also act as barriers against the escape of radiations from the seals. Sleeves 62, 63 spacers 64, 65 bearings 66, 67 and gland nut 68 are also provided to space the elements apart and support them in position. The bearing also includes spaced inner and outer race elements 109, 108. The inner element 109 is held in place on the shaft through bearing element 67 and set screw 111, seating in a peripheral recess in element 67. The outer element 108 is carried by bearing element 66 so that together they form a race for ball bearings 110. The various voids in the aforementioned construction may be filled with concrete or other shielding material, as indicated at 12, 103. Hence, there is no direct path axially of the shaft from the interior of the cell to the outside along which radiations may escape.

The lower end of the shaft mechanism and housing which extends into the cell is provided with a joint coupling which has a slight universal movement and which is generally indicated at 11. Details of the coupling may be found in Fig. 5. It includes female socket portion 113 and male portion 114 appropriately keyed to the shaft 10 and supported on the lower end thereof by nut 69 and joined to the upper end of shaft 72 by a similar nut 112. These socket portions may be keyed to the shafts 10 and 72 by the conventional or standard longitudinal slot and key to insure rotation with the shafts. The female socket 113 provides a yoke whose arms 115, 115 straddle the extension 116 of the male portion of the coupling. Formed in the arms of female socket 113 are recesses into which rubber gaskets 117, 117 are seated and held in place by pins 119, 119 and cotter 135, 135. The pins 119, 119 are hardened and polished and serve as bearing surfaces for tapered bosses 118, 118 on extension 116. Thus when the centrifuge basket 22 is rotated rapidly, the pins 119, 119 and rubber gaskets 117, 117, respectively, receive the wear and absorb the shock while providing a resilient cushion which facilitates flexing of the shafting arrangement.

Referring now to Fig. 3, the universal joint 11 referred to under Fig. 2 and shown in detail in Fig. 5 is also shown in this figure. The male portion of this joint attached to shaft 72 which carries the centrifuge is associated with a bearing which is supported by a plurality of resilient supports, as for example rubber rings 16. This is analogous to the construction in ordinary suspended centrifuges and permits the centrifuge basket to sway or otherwise seek its own balance depending upon the loading thereof, without affecting the operation of drive shaft 10. In this connection it may be noted that the suspension of casing 4 by flange 75 between rings 16 permits displacement of the casing and drive shaft as the centrifuge basket is displaced.

Retainer 4 supports bearing 133 which in turn supports male portion 114. Ring 136 holds bearing 133 by means of cap screws 137, 137 that engage into retainer 4 which rests between resilient rings 16 as indicated above. Also fastened to retainer 4 by cap screws 134, 134 is shield 132. This shield serves the same purpose as do ring members 17 whose function will be explained later. The entire coupling assembly is enclosed in hous-

ing 3 and yoke 130 through bolts 131, and the arrangement is supported by the legs of the yoke.

The universal joint is connected directly to the centrifuge basket 22 by an ordinary shaft excepting that ring members of comparable construction indicated at 17 may be positioned along this shaft. The function of parts 17 are to prevent liquid flowing down the shaft or creeping up the shaft from the centrifuge basket. That is, any radioactive liquid which tends to creep up the shaft 10 out of the centrifuge upon reaching one of these rings would be thrown off the shaft. On the other hand, any lubrication leaking down the shaft would likewise be thrown off by these rings before it has an opportunity to reach the centrifuge basket.

The centrifuge construction is very much similar to the usual solid bowl centrifuge. An outer housing portion 23 serves to inclose the centrifuge basket 22 and the upper face thereof is partially closed by a collector cover 122 joined to the upper peripheral flange thereof. The housing 23 in the lower extremity of its side wall is provided with an opening or outlet for the reception of the end of a flanged pipe or conduit 24 which is secured in place therein by welding or otherwise. The conduit may be connected with other conduits whereby the separated liquids from a plurality of centrifuges may be conducted to other cells for treatment or storage. Likewise, the centrifuge is equipped with an inlet conduit or pipe 18 which extends through the top wall or cover 122 of the housing 23 down into the basket 22, terminating at the lower extremity thereof. This latter conduit may serve to feed materials to be centrifuged into the basket 22 for processing. A skimmer 19 may be of tubular material and may have a substantially U-shaped portion. It passes through an opening in arm 76 and is secured to said arm. The arm 76 is mounted on a block 120 carried on the periphery of a shaft 77 which passes up through the top wall or cover of housing 23 and is journaled in a suitable bearing 121 carried by extension 123 of cover 122 to permit rotation about a vertical axis. The shaft 77 carries a gear wheel which is meshed with and actuated by a worm gear 78 mounted to turn with shaft 21, which shaft is journaled in bearings 79, 80. Rotation of shaft 21 turns shaft 77 and arm 76 and moves the lower end of skimmer 19 with respect to the inner wall of basket 22, in such a manner that the end of the skimmer may be made to approach or move away from the basket wall. Shaft 82 carries a worm gear which meshes with gear 124 on shaft 21. Any conventional bearing and support means may be employed to support shaft 82 at this point. Shaft 82 then extends up through barrier 7 in a casing arrangement somewhat similar to that previously described in connection with the basket drive shaft and is generally designated 6. By rotation of shaft 82, the skimmer 19 is manipulated. The movement of shaft 82 causes the end of the skimmer 19 to travel back and forth in an arcuate path. When the centrifuge is operating to separate precipitate, the skimmer may be moved in away from the edge of the basket to an inoperative position. When it is desired to skim, the operator, by rotating shaft 82 from outside of the barrier, can move the skimmer to any desired position to skim adjacent the wall of the centrifuge basket. The precipitate-free liquid may then pass out through the other free end of the skimmer and into the housing 23 of the centrifuge. If desired for better positioning, the skimmer may also be given a vertical movement by modification of the actuating mechanism in any conventional manner.

The basket 22 has a conical bottom portion, and an upper inturned lip which extends inwardly from the upper edge of the basket. Joined to the bottom and extending upwardly through the central portion of the basket 22 is the shaft 72 for rotating the basket. Centrally of the basket is an internally positioned perforated ring 25 which is joined to the inner walls of the basket at an intermediate portion thereof and extends from the inner

walls thereof towards the center. The ring functions very much like a baffle, causing better distribution within the centrifuge basket and during the separation of the liquid from the precipitate, prevents too rapid flow of the liquid out of the lip edges of the centrifuge basket.

The mechanism may be driven by an air motor arrangement such as is disclosed in Fig. 4. An air motor 26 is shown, although various other types of motors may be employed for the purpose. The motor 26 is supported in a circular support 83 having set screws 84 passing therethrough to engage the collar 125 on the motor. The support 83 has a flange for engagement with web 126 extending inwardly from the wall of housing 2, and studs 85 secure the support 83 to web 126. The second support 86 has a flange portion for engagement with web 88 and is secured to the web by studs 87 which pass through mating openings therein. The support 86 also has an angular bore 89 in its central portion for the reception of, and screw threaded engagement with a pipe 90 to feed air to the bore and from the bore into the motor. The upper end of motor 26 is seated in the opposed end of the bore, which serves as a socket to retain the motor in place and also provides a channel for air flow to the motor. The shaft of motor 26 is coupled through a coupling 27 of conventional tubular construction to the shaft section 102 which extends out of the barrier and carries tachometer 28 of conventional type. Set screws 127, 128 are employed to affix coupling 27 to the two shafts although the upper end of shaft 102 is screw threaded into the coupling. The electrical leads 29 of the tachometer 28 may pass out through a conduit 91 to the instrument panel in the usual manner so that the operator may determine the speed of the centrifuge.

The operation of the suspended type of centrifuge is somewhat as follows: Liquid, containing precipitate to be separated, is fed into the centrifuge basket through conduit 18. The centrifuge basket 22 is rotated at high speed through the shaft sections 102, 9, 10, 72 and the precipitate slurry distributes itself on the inner walls of the centrifuge basket 22. The liquid from the precipitate which has been thrown out by the centrifugal force flows over the upper lip of the centrifuge basket 22 and out of the centrifuge housing 23 through conduit 24. After such slurry or precipitate has been built up on the inner wall of the centrifuge basket, flow of liquid through pipe 18 into basket 22 is stopped and skimmer 19 may be moved towards the inner wall of the basket by manipulation of the shafts 82 and 21 as previously indicated. As the basket continues to rotate, the lower end of skimmer 19 dips into the liquid along the wall of the basket, and the momentum and pressure of the moving liquid in the basket causes such liquid to be forced up the tubular skimmer 19 and out the free upper end into the housing 23 where it may flow out through conduit 24, thus removing substantially all of the liquid, leaving the precipitate on the walls of the basket to be removed by other well-known means, such as by scraping or with appropriate solvents.

Referring to the modification shown in Fig. 6, many of the parts are similar to those described above. That is, the driving means may comprise an air motor 46' supplied with air under pressure through conduit 47'. The motor is connected through a tachometer 48' to a shaft 72' for driving the centrifuge basket 42'. Leads 49' from the tachometer to an instrument panel are provided and pass out through conduit 101', screw threadedly mounted on housing 92'.

The connection with the centrifuge basket may be through coupling 51' which bridges shafts 9', 72' and is keyed to them by the usual longitudinal keys and slots. In addition, appropriate set screws 127', 128' may be employed to affix the coupling to the shafts. In this construction the drive may be more direct and rigid since there is not involved the problem of a long drive

shaft through several feet of shielding, for the entire assembly is placed within the cell.

The centrifuge bowl and other elements are substantially similar in construction to those described above and do not require extended comment excepting to point out that in the present construction the bowl's weight and rotation is supported in a plurality of sets of roller bearings designated 52' and 53'. Lubrication for these bearings may be provided as indicated at 54'.

However, in the construction of Fig. 6 there is the problem that liquid leakage may occur so as to contaminate the lubrication as well as flow down the shaft into the motor housing. Hence, to prevent this a number of seals, as shown, for example at 56' and 58' may be provided. These seals may comprise offset and overlapping concentric rings. However, inward leakage through the seals is prevented or retarded by providing positive air pressure introduced through conduits such as 55' at suitable points in the assembly. It has been determined that about a half pound of air pressure should provide ample draft of air to prevent inward leakage. A brake is provided at 57' with a drum 160' mounted on shaft 72' by key and set screw. Spring element 61' serves to normally maintain the lining away from the brake drum 160' by engaging against pivoted arm 62' carried by hanger elements 63' and carrying shoulders 64' for moving the brake lining and band towards and away from the drum. A suitable opening 59' may be provided for in the centrifuge housing for access to the centrifuge basket, and a suitable outlet 60', corresponding to outlet 24 of the first modification, is provided in association with the centrifuge housing. A remotely controlled skimmer and feed pipe (not shown) similar to those described above in connection with the suspended construction may be provided. The opening 59' may be normally closed with a cover 65' hingedly mounted through pivoted lever 66'.

A frame or housing 92' serves to carry motor supports 93', 94' through spaced bracket rings or webs 95', 96' and bolts 97', 97' and 98', 98', respectively. A circumferential flange 99' is carried by the upper end of frame 92' and serves as a base for the bearings and the supports which carry the centrifuge casing 100' and the basket 42'.

Plate 102' serves as the base of a cylindrical container 104' and rests upon flange 99' which is secured thereto through bolts 103', passing through aligned openings therein. As previously indicated, the container provides an oil reservoir 54' and appropriate wicking 105' may extend up through a bore in the container from the bottom of the reservoir to feed lubricant to roller bearings 53' for the bowl or basket 42'. The upper portion of the container 104' carries casing 100' clamped thereto through clamping elements 106', studs 107', and nuts 118'.

The general mode of operation of this modification is very much similar to that of the modification previously described in that basket 42' is rotated at high speed by air motor 46'. The separated liquid passes over the upper lip 108' of the basket and out through outlet or conduit 60'. Partition ring 109', with perforations adjacent its juncture with the inner wall of the basket 42', serves to function as a baffle, as previously described, to provide better distribution within the centrifuge basket. At the end of the operation when the feeding of liquid to the bowl through the feed line (not shown) has ceased, the balance of the separated liquid may be removed through a skimmer while the bowl continues to rotate. When this has been completed, the motor is stopped and the bowl is brought to rest. The precipitate is removed by scraping or with a solvent. For the purpose of bringing the basket to rest, the brake 57' may be applied to its drum in the usual manner.

Having thus described my invention, I claim:

1. A centrifuge system for separating radioactive materials comprising a casing adapted to be disposed behind a thick walled barrier, a basket rotatably positioned within the casing, and means passing through the walled barrier for suspending and rotating the basket, said means including a series of shaft sections for extending through successively smaller stepped bores of the barrier, said sections becoming progressively smaller towards the basket to resist the passage of radiation.

2. A centrifuge system for separating radioactive materials comprising a casing adapted to be disposed within a thick walled inclosure, a basket rotatably positioned within the casing, and means passing through the walls of the inclosure above the casing to suspend and rotate the basket, said means including a series of shaft sections of progressively smaller diameter extending through a bore of progressively smaller size to limit the passage of radiations.

3. A centrifuge system for separating radioactive materials comprising a casing adapted to be disposed within a thick walled inclosure, a basket rotatably positioned

15

20

within the casing, and means passing through the walls of the inclosure above the casing for suspending and rotating the basket therein, said means including a series of shaft sections for extending from the exterior of the inclosure to the basket through successively smaller bores in the inclosure, said sections becoming progressively smaller in diameter as the basket is approached for co-operation with the inclosure to reduce the passage of radiation, and at least one universal joint between the sections to permit flexing.
